Primary Examiner — Marissa J Cash(74) *Attorney, Agent, or Firm* — Cognition IP, P.C.;
 Bryant Lee(57) **CLAIM**

The ornamental design for an aircraft, as shown and described.

DESCRIPTION

FIG. 1 is a top perspective view of an aircraft showing my new design;

FIG. 2 is a top plan view thereof;

FIG. 3 is a bottom plan view thereof;

FIG. 4 is a front elevation view thereof;

FIG. 5 is a rear elevation view thereof;

FIG. 6 is a right side elevation view thereof; and,

FIG. 7 is a left side elevation view thereof.

The broken lines in the drawings showing elements of the aircraft represent unclaimed portions of the aircraft and form no part of the claimed design.

1 Claim, 5 Drawing Sheets(56)
